UNITED STATES PATENT OFFICE.

WILLIAM PEARCE, OF AKRON, OHIO, ASSIGNOR TO THE B. F. GOODRICH COMPANY, OF AKRON, OHIO, A CORPORATION OF OHIO.

DESIGN FOR A GOLF-BALL.

41,817.

Specification for Design.

Patented Oct. 3, 1911.

Application filed July 11, 1910. Serial No. 571,508. Term of patent 14 years.

To all whom it may concern:

Be it known that I, WILLIAM PEARCE, a subject of the King of England, residing in the city of Akron, in the county of Summit and State of Ohio, have invented a new, original, and ornamental Design for Golf-Balls, of which the following is a specification, reference being had to the accompanying drawing, forming part thereof.

Figures 1 and 2 are plan and elevational

views, respectively, of a golf ball, showing my new design.

I claim:

The ornamental design for a golf ball, as shown.

WILLIAM PEARCE.
